UNITED STATES PATENT OFFICE.

LEONARD L. ELDRIDGE, OF SAN ANTONIO, TEXAS.

BUILDING CONSTRUCTION.

Application filed May 28, 1923. Serial No. 641,936.

To all whom it may concern:

Be it known that I, LEONARD L. ELDRIDGE, citizen of the United States, residing at San Antonio, in the county of Bexar and State of Texas, have invented certain new and useful Improvements in Building Construction, of which the following is a specification.

This invention relates to new and useful improvements in building construction.

The object of the invention is to provide means whereby a re-inforced fire proof wall may be constructed in a simple and practical manner at a reasonable expense and without the services of highly skilled labor.

Another object is to provide units in the form of vertical slabs which may be assembled in a substantial and expeditious manner to form a wall which may be easily finished and ornamented.

A further object of the invention is to provide T-shape slabs provided with projecting re-inforcing means and assembled so that the projecting re-inforcing means is received in vertical joints between the edges of adjacent slabs and cemented, whereby the slabs are bonded together on both sides of the wall.

Certain features of my Letters Patent issued on April 26th, 1921, for building construction are used in this invention, but no separate claim to the same is herein made.

A construction designed to carry out the invention together with other particular features of the invention will be hereinafter described.

The invention will be more readily understood from a reading of the following specification and by reference to the accompanying drawings, in which an example of the invention is shown and wherein:

Fig. 1 is an isometric view of a corner of a wall constructed in accordance with my invention, portions of the wall being omitted.

Fig. 2 is a horizontal cross sectional view of the wall,

Fig. 3 is an enlarged cross-sectional view showing the manner of setting a window frame in the wall,

Fig. 4 is a plan view showing the cap lacing, and

Fig. 5 is a vertical sectional view with a floor joist in place.

In the drawings the numeral 10 designates a base wall or under-pinning of suitable di-

mensions and material, such as concrete. The base wall is formed with a longitudinal top channel 11 which has an ample ledge on each side thereof. A plurality of T-shaped vertical slabs 12 are provided and each formed with a central longitudinal tongue 13. The vertical edges of the slabs are bevelled at 14 so as to form V-shaped seams or recesses between the adjacent edges when the slabs are assembled.

The slabs have their tongues 13 extending beyond their faces at each end to form lugs 15 and 16 respectively and the channel 11 has a width substantially equal to the depth of the tongues. The slabs are placed on each side of the wall with their tongues directed inwardly in alternate relation and spacing the slabs apart. This forms a hollow wall of substantial construction.

The slabs are suitably re-inforced with a longitudinal angular element 17 preferably formed of large mesh wire fabric, but which may be of any suitable material. The reinforcing element is made to project from the outer edge of each tongue 13 and is received between the bevelled edges 14 when the slabs are assembled. The projecting portions of said elements are of such length as to terminate in the V-shape recesses so that they may be concealed when the recesses are filled.

The slabs are made comparatively thin and of such dimensions as to be readily handled by one man. A slab ten inches wide and ten feet long has been used successfully, but the dimensions may be varied to meet the building conditions. The slabs are set up on the base 10 with their lugs 15 in the channels 11. The tongues 13 space the slabs apart and also form vertical air spaces in the wall. The base extends beyond the outer faces of the slabs to form a water-table and also extends beyond the inner faces to provide a ledge on which floor joists 18 may rest.

Shallow pans 19 are placed between the lugs 16 at the top of the wall to cover the spaces between the tongues. Tie rods 20 are laced around the lugs above the pans. A cap 21 is formed by suitably molding concrete or other plastic material flush with the faces of the slabs and the tops of the lugs, whereby the lacing is embedded and the top of the wall bonded. The pans support the cap and prevent filling of the air spaces.

Cement or equivalent material is troweled

into the V-shaped recesses 14 to form joints in which the projections of the re-inforcing elements 17 are embedded and bonded. The two sides of the wall are bound together by the joints and the latter when finished give the slabs a smooth outer surface, which may be plastered or otherwise covered. If desired concrete or the like may be poured into the channel 11 between the lugs 15 before the pans 19 are placed, whereby the slabs are tied to the base.

The slabs when set on the base 10 will with the cap 21 give a height suitable for a one story building. For windows and doors shorter slabs may be cast and set above and below the same. In Fig. 3 I have shown one side 22 of a window frame fitted into one of the slabs against the tongue 13 thereof. A joint 23 is formed with the bevelled edge 14 of the inner slab and one edge of the frame is embedded in said joint. The inner side of the wall is plastered and the casing 24 nailed to the frame.

Various changes in the structure as well as modifications and alterations may be made within the scope of the appended claims.

What I claim, is:

1. In a building construction, a hollow wall including a plurality of oppositely arranged slabs formed T-shaped in cross section, T-shaped re-inforcing elements embedded in the slabs and projecting from the vertical edges of the tongues, the projecting portions of said elements being received in the space between the opposed slabs and cemented therein to provide the sole bonding means for said projecting portions of the reinforcing elements.
2. A re-inforced building slab T-shaped in cross-section and having its vertical edges along its face portion beveled, a metallic T-shaped re-inforcing element embedded in the

slab and having a vertical portion projecting from the outer edge of the tongue of the slab, the beveled edges of the slab being free from projections of the reinforcing element.

3. In a building construction, a hollow wall including a plurality of oppositely arranged slabs formed T-shaped in cross-section, the adjacent vertical edges of the slabs being bevelled on the faces thereof and forming V-shaped recesses, and re-inforcing elements embedded in the tongues of the slabs and extending into the said V-shaped recesses of the slabs on the opposite sides of the wall and cemented therein, to provide bonding means in said recesses for the slabs.

4. A reinforced building slab T-shaped in cross-section and having its vertical edges along its face portion beveled, a foraminous reinforcing element embedded in the slab vertically thereof and T-shaped in cross-section, the intermediate portion of the reinforcing element extending through the tongue of the slab and projecting from the outer vertical edge of said tongue along a substantial portion thereof.

5. In a building construction, a hollow wall including a plurality of oppositely arranged slabs formed T-shaped in cross section, the adjacent vertical edges of the slabs being beveled on the faces thereof to form V-shaped recesses at the joints between the slabs, and T-shaped foraminous reinforcing elements embedded in the slabs and projecting along the vertical edges of the tongues and extending into the recesses, and cement filled in the recesses and in which the projecting portions of the reinforcing elements are embedded to bond the wall.

In testimony whereof I affix my signature.

LEONARD L. ELDRIDGE.
